CAR CONSTRUCTION

Minot C. Blest, Avalon, Pa., assignor to Pressed Steel Car Company, Pittsburgh, Pa., a corporation of New Jersey

Application January 15, 1931, Serial No. 508,827

9 Claims. (Cl. 105—377)

My invention relates to railway cars and particularly that type of car known as a refrigerator car and has for its object the provision of a hatch cover and sealing plug which automatically seals the hatch opening as the cover is lowered into position.

Another object of my invention is to provide means whereby the plug is readily released from sealing position as the hatch cover is raised.

10 A further object of my invention is to provide a novel means for holding the cover and plug in partly opened position to provide ventilation through the hatch opening.

15 Other objects and advantages of my invention will be disclosed as the description proceeds.

Referring to the drawings, Fig. 1 is a plan view of a portion of the roof of a refrigerator car showing a hatch cover and sealing plug embodying my invention; Fig. 2 is an end elevation of the car 20 showing my invention; Fig. 3 is a section taken along the lines 3—3 of Fig. 1 and shows in elevation the hatch cover and plug; Fig. 4 is a modification of the means shown in Fig. 2 for securing the cover in partly raised position; Fig. 25 5 is a plan view of the link 6 and Fig. 6 is a section along the lines 6—6 of Fig. 5.

Referring now in detail to the drawings where like reference characters refer to like parts, reference character 1 indicates a refrigerator car 30 having a hatch opening 2, a hatch cover 3, a plug 4 for sealing the hatch opening and a hatch cover operating handle 5 secured to the cover and pivotally mounted in brackets secured to the car adjacent one side of the hatch opening. The plug 35 4 is suspended from the cover 3 by means of links 6 and 7 which are of unequal length and mounted on opposite sides of the plug. The shorter link 6 connects the plug and hatch cover at the side of the hatch opening adjacent the pivotal connection of the handle to the car body which side, for convenience, will hereinafter be called the rear of the hatch opening. The link 7, connecting the plug to the cover adjacent the front of the opening, is pivotally mounted on the cover 40 45 3 and secured to the plug 4 by means of a member 8 mounted on the plug. The member 8 is an elongated end portion to provide for movement of the link relative to the plug.

From an inspection of Fig. 3 of the drawings 50 it will be apparent that the upper portion of the hatch opening slopes inwardly for a portion of the depth of the opening and the hatch plug has a resilient insulating member surrounding the periphery of the plug so as to permit the plug when moved downwardly to be forced into en-

gagement with the sides of the opening to seal the opening against escape of the cooling medium or the entrance of the outer air.

As shown in Figs. 1 and 3 of the drawings the operating handle is preferably of a substantially U-shape with the free ends of the arms being pivoted to the car body adjacent the rear of the hatch opening. Inwardly of such pivotal connection, the arms are secured to the hatch cover so that in addition to forming a handle for operating the cover the ends provide a hinged connection between the hatch cover and car body. The closed portion of the operating handle is preferably bifurcated so as to form a guide for a member 9 which is pivotally mounted to the car body adjacent the front of the hatch opening and which is disposed over the hatch cover and operating handle when the cover is in closed position. Within the bifurcation and secured to the handle is a tooth-shaped member 10 which provides a bearing for the member 9 as the hatch cover is raised and which is adapted to engage with suitable spaced notches 11 in the member 9 to support the hatch cover in partly raised position. Suitably spaced openings 12 in the member 9 which coincide with a similar opening 13 in the bifurcated portion of the handle provide means for the insertion of a locking member 14 to secure the hatch cover in partly raised or completely closed position and prevent accidental movement of the hatch cover during the time the car is in transit or other times when it may be desirable to prevent the changing of the position of the hatch cover.

Assuming the hatch cover to be in closed position as shown in Figs. 1 and 3 and it is desired to raise the cover into the position shown in dot-and-dash lines on Fig. 3 the action is as follows: the operator removes the locking pin 14 from the openings 12 and 13 of the member 9 and handle 5, after which the handle 5 is rotated about its pivotal connections to the car body. As will be apparent from Fig. 3 the length of the link 7 and its method of attachment to the plug 4 permits the initial opening of the front part of the cover while allowing the plug to remain in position. As the hatch cover continues its upward movement the shorter link 6 at the rear of the plug causes an upward movement of the rear of the plug, breaking the seal 50 between the plug and the adjacent side of the hatch opening after which the front link 7 lifts the front of the plug and for the remainder of the opening movement the hatch cover and plug move as a unit. The importance of the initial 55

- unequal movement of the plug within the opening is more readily appreciated upon consideration of the fact that the plug was forcibly moved down into the opening to form a seal and usually becomes frozen in place by the moisture on the sides of the hatch opening turning to ice. The advantage in having the rear end of the plug separate from the hatch opening before the front end is readily apparent since the handle is fulcrumed to the car at the rear of the opening and greatly increased leverage is obtained over that which would be effective were the plug and cover to move as a unit throughout the entire opening movement of the cover.
- 15 During the time the cover is rising the member 9 bears on the member 10 secured within the bifurcation of the handle and this member 10, in combination with the handle, acts as a guide to move the member 9 upwardly and the notches 20 in the member 9, which are automatically engaged by the toothed member 10, permit the cover to be supported in various partly opened positions. If desired, a locking member 14 may be inserted through the openings 12 and 13 in 25 the handle and member 9 so as to lock the cover in this partly raised position to provide for the ventilating of the interior of the car body. If desired, the cover may be completely opened and laid back against the roof of the car body and the member 9 may be moved on its pivotal connection so as to provide a free and uninterrupted 30 entrance to the hatch opening. When the hatch cover is moved to closed position, the rear portion of the plug moves into the hatch opening first and pivoting about the link 6 automatically 35 centers itself within the opening before the cover reaches closed position. This centering of the plug is permitted by the link 7 pivoting and sliding within the member 8. After the plug has thus centered itself within the opening, the cover in moving downward, engages with the front and rear portions of the plug forcing the plug into a sealing position as the cover comes to rest over the opening.
- 40 A modification in the means for holding the cover in partly raised position is shown by Fig. 4. Here the member 10 is replaced by a bar 15 and the notches 16 in the member 9 are rounded at their inner end so as to form a socket into which the member 15 moves. In this manner the members 15 and 9 are held against separation until the locking member 14 can be inserted within the openings 12 and 13.
- 45 Having thus described the invention what I claim as new and desire to secure by Letters Patent is:
- 50 1. In a refrigerator car in combination, a hatch opening, a hatch cover hinged at one side of said opening and a hatch plug suspended from said cover so as to be movable relative thereto, said plug automatically centering itself within said opening independently of said cover upon movement of the cover into a position closing the hatch opening.
- 55 2. In a refrigerator car in combination, a hatch opening, a hatch cover hinged at one side of said

opening, a hatch plug for sealing said opening and suspended from said cover, said plug automatically centering itself within said opening independently of said cover as the cover is lowered and being forced into sealing position as the cover comes to rest over said opening.

3. In a refrigerator car in combination, a hatch opening, a hatch cover hinged adjacent one side of said opening, a plug for sealing said opening, links connecting opposite sides of said plug to 10 said cover, said links being of unequal length.

4. In a refrigerator car in combination, a hatch opening, a hatch cover, a plug for sealing said opening, an operating handle secured in fixed relation to said cover and hinged to the car 15 adjacent one side of said opening, and links of unequal length connected adjacent opposite sides of the plug and to said hatch cover.

5. In a refrigerator car in combination, a hatch opening, a hatch cover, a plug for sealing said 20 opening and suspended from said cover for movement relative thereto, an operating handle secured in fixed relation to said cover and hinged to the car adjacent one side of said hatch opening, a member hinged to the car adjacent to and overlapping said handle when the cover is in closed position, a notch in said member and a tooth on said handle disposed beneath said member, said tooth engaging with said notch to support the cover in partly opened position.

6. In a refrigerator car, in combination, a hatch opening, a hatch cover hinged to the car adjacent one side of the opening, a hatch plug for sealing said opening and suspended from said cover, said hatch plug being operable upon movement of the cover and having an opening movement reversed in direction from the opening movement of said cover after which the plug follows the cover in opening.

7. In a refrigerator car, in combination, a 40 hatch opening, a hinged cover for the opening adapted to lie substantially flat across the opening, a hatch plug suspended from the cover, an operating handle for the cover hinged to the car and adapted to exert an initial opening movement of the plug adjacent but one margin of the 45 plug.

8. In a refrigerator car, in combination, a hatch opening, a hatch cover, a plug for sealing within said opening and movably suspended from said cover, an operating handle secured to the 50 upper face of said cover and hinged to the car adjacent one side of said plug.

9. In a railway car, the combination with a hatch opening, a hinged cover for the hatch opening, a handle operatively associated with the cover and pivoted to the car, a hatch plug depending below the cover and adapted to seat within the opening, a means pivotally suspending said plug from adjacent one margin of the cover, and a link pivotally suspending the plug from adjacent the opposite margin of the cover so as to permit restricted movement of the plug to and from the cover upon movement of the cover relative to the hatch opening.
